Patented Feb. 23, 1926.

UNITED STATES PATENT OFFICE.

EDWARD J. B. IRVING, OF TRAIL, BRITISH COLUMBIA, CANADA.

AUTOMOBILE LOCK.

Application filed May 16, 1924. Serial No. 713,796.

To all whom it may concern:

Be it known that I, EDWARD J. B. IRVING, citizen of the Dominion of Canada, residing at Trail, in the Province of British Columbia, Canada, have invented certain new and useful Improvements in Automobile Locks, of which the following is a specification.

This invention relates to an automatic lock for the self-starting mechanism of an automobile engine, which lock will retain the pinion of the self-starting mechanism in the out-of-use position, that is, clear of engagement with the gear wheel on the driving shaft of the engine. This retaining means can only be released by the party having a key for that purpose.

When the lock has been released and when the pinion of the self-starter, having accomplished the starting of the engine, moves endwise along its screw and out of mesh with the gear wheel on the engine shaft, it will again automatically latch in the out-of-use position to prevent its being again moved into mesh, unless its retaining latch is released with the key in the possession of the owner or authorized driver of the machine.

The means by which these results are attained is fully described in the following specification, reference being made to the drawings by which it is accompanied, in which:

Fig. 1 is a vertical section showing the pinion of the self-starter as retained against movement into mesh with the gear wheel of the engine.

Fig. 2 is an end elevation of the same, and

Fig. 3 is a section of the lock release to an enlarged scale.

In these drawings 2 represents the threaded shaft of the self-starting mechanism, such as a Bendix drive, and 3 the driving pinion of that mechanism, which is endwise movable along the screw of the shaft 2 to bring it into mesh with the gear teeth 4 of the engine fly wheel. This pinion 3 automatically moves backward along the screw out of engagement with the gear teeth 4 when the speed of the engine exceeds that of the self-starting mechanism.

Secured to or integral with the hub of the pinion 3 is a collar 5 leaving a circumferential groove 6 between that collar and the body of the pinion. The outer edge of this collar 5 is bevelled, as shown in Fig.

1, to engage the correspondingly bevelled end of a latch bolt 7, the stem of which bolt is endwise movable in a tubular guide 9.

This tubular guide 9 of the bolt stem 8 passes upward through the casing 11 of the starting mechanism and through the foot-board 12 to a position convenient to the driver, that is, adjacent the instrument board. The upper end of it is closed with a cap or plug and between this plug and the upper end of the stem 8 is a light spring 10 which holds the latch bolt at the lower limit of its movement.

Secured to the guide tube 9 adjacent the upper end of the latch bolt stem is a lock 13 of approved make, the key 14 of which, after passing the wards of the lock, will engage the square shoulder of a notch 15 in the stem 8 and lift that stem a sufficient amount to release the end of the latch bolt 7 from the collar 5, and will permit the pinion 3 to be moved endwise on its screw 2 to mesh with the gear teeth 4 and effect starting of the engine.

When hold of the key 14 is released, the spring 10 will carry the latch bolt down to its normal position, so that when the pinion of the starting mechanism having accomplished its work, is retired out of mesh with the gear teeth 4 it is automatically latched in the out-of-use position.

Having now particularly described my invention, I hereby declare that what I claim as new and desire to be protected in by Letters Patent, is:

1. An anti-theft device for an automobile, comprising the combination with the driving pinion of the starting mechanism, of means, releasable with a key, for retaining the pinion in the out of mesh position in relation to the geared wheel of the engine shaft.

2. An anti-theft device for an automobile, comprising the combination with the pinion of the self-starting mechanism of an automobile, of means for automatically retaining it in the out of mesh position in relation to the driving wheel of the engine shaft, and a key for releasing said retaining means.

3. An anti-theft device for an automobile, comprising the combination with the pinion of the self-starting mechanism, of a latch bolt adapted to automatically engage the pinion of the starting mechanism and retain it in the out of mesh position, a spring tending to hold the latch in the retaining

position, and a lock protected means for lifting the latch and releasing the pinion.

4. An anti-theft device for an automobile, comprising the combination with the pinion of the self-starting mechanism, of a latch bolt designed to automatically retain the pinion in the out of mesh position in relation to the driving wheel of the engine shaft, and means protected with a lock for releasing the latch and permitting the pinion to be moved into mesh.

5. An anti-theft device for an automobile, comprising the combination with the pinion

of the self-starting mechanism, which pinion has a circumferential groove around its hub, 15 a latch bolt adapted to fit the groove and retain the pinion against endwise movement, said bolt having a stem which is vertically 20 slideable in a tube secured to the frame of the machine, a spring tending to hold the latch in the groove of the pinion, and a key adapted to engage the stem and lift the latch and release the pinion.

In testimony whereof I affix my signature.

EDWARD J. B. IRVING.
